GRINDING WHEEL DRESSER

Cecil D. Chandler, Odessa, Tex.

Application September 7, 1951, Serial No. 245,543

3 Claims. (Cl. 125—11)

1

This invention relates to grinding wheel dressers and more particularly to a grinding wheel dresser adapted to be mounted on a grinding machine frame or bed and carry a diamond point in contact with a rotating grinding wheel to dress the latter to desired form.

It is among the objects of the invention to provide an improved grinding wheel dresser which can be magnetically mounted on a metal base or frame adjacent a grinding wheel without the use of clamps or brackets and will carry a diamond point implement in engagement with the wheel; which includes manually operated means for moving the dressing point in a straight line transversely of the wheel and for adjustably moving the point toward and away from the wheel; which can be used to trim a beveled surface at any desired angle on the wheel; which can be readily moved from one grinding machine to another and can be conveniently stored when not in use; and which is simple and durable in construction, economical to manufacture, and positive and effective in operation.

Other objects and advantages will become apparent from a consideration of the following description and the appended claims in conjunction with the accompanying drawing wherein:

Figure 1 is a side elevational view of a grinding wheel dresser illustrative of the invention;

Figure 2 is a top plan view of the grinding wheel dresser illustrated in Figure 1;

Figure 3 is a longitudinal cross sectional view on the line 3—3 of Figure 2; and

Figure 4 is a transverse cross sectional view on the line 4—4 of Figure 1.

With continued reference to the drawing, the grinding wheel dresser illustrated therein comprises a base, generally indicated at 10, of rectangular shape including a magnetized base block 11, a top block 12 superimposed on the base block 11 and having a groove 13 extending longitudinally thereof and opening to the side thereof remote from the bottom block, and a separator plate 14 of non-magnetic material interposed between the top block 12 and the bottom block 11 to space the magnet 11 from the block 12 of magnetically permeable material and maintain a substantially symmetrical magnetic field for the magnet.

The groove 13 is undercut along at least one side thereof, as indicated at 15, and a wear plate 16 is disposed in the groove against the undercut side 15 thereof. Set screws 17 extend through tapped holes in the portion of the top block 12 between the undercut side of the groove and the adjacent side of the top block and bear at their

inner ends against the adjacent side of the wear plate 16 for a purpose to be presently described.

The bottom block 11 has a flat bottom surface and is provided with spaced apart apertures extending therethrough with their center line substantially perpendicular to the bottom surface of the block and the separator plate 14 is provided with apertures registering with the apertures in the bottom block. The top block 12 is provided with tapped holes or recesses registering with the apertures in the separator plate and screw fasteners 18 extend through the registering apertures in the bottom block and the separator plate and are threaded into the corresponding tapped holes in the top block to rigidly secure the components of the base together and provide the base of rectangular shape.

End plates 20 and 21 are secured to the base 10, one at each end thereof, by suitable means, such as the screws 22 extending through apertures in the end plates and threaded into tapped holes in the bottom block 11 of the base.

The end plates 20 and 21 are provided with apertures, as indicated at 23 and 24 respectively, opening into the groove 13 at the corresponding ends of the latter and a screw shaft 25 extends through the groove 13 and has reduced end portions 26 and 27 journaled in the end plate apertures 23 and 24 respectively. A hand crank 28 is secured on one end of the screw shaft 25 for imparting rotational movement in either direction to the latter.

A slide block 30 of rectangular shape is mounted on the top block 12 of the base at the side of the top block remote from the bottom block 11 and has spaced apart keys 31, 32 and 33 slidably received in the groove 13 and provided with beveled faces contacting the adjacent undercut side of the wear plate 16 to hold the slide block against separation from the base while permitting sliding movement of the slide block longitudinally of the base. The two end keys 32 and 33 are provided with bores or apertures loosely receiving the screw shaft 25 and the center key 31 is provided with a screw threaded aperture through which the screw shaft is threaded, so that the slide block is moved longitudinally of the base when rotational movement is imparted to the screw shaft by the crank 28.

The keys are maintained against play or looseness in the groove 13 and the frictional resistance to movement of the slide block relative to the base is controlled by adjusting the set screws 17 to adjustably vary the pressure of the wear plate 16 against the beveled faces of the keys.

The slide block 30 is provided with a bore 35 extending transversely therethrough substantially at the mid-length location of the slide block and with the center line of the bore substantially at right angles to the axis of the screw shaft 25 and inclined at an angle of approximately 15 degrees to the flat bottom surface of the bottom block 11 of the base. The bore 35 is provided with a counterbore extending from the end of the bore nearest the bottom surface of the base to a location intermediate the length of the bore and the remainder of the bore from the counterbore to the end of the bore 35 most distant from the bottom face of the base is screw threaded. A dressing point carrier 36 is slidably mounted in the counterbore portion of the bore 35 and projects from the end of the bore nearest the bottom surface of the base and this carrier carries a point holder 37 which projects from the end of the carrier disposed externally of the slide block 30 to engage the surface of an adjacent grinding wheel, as indicated at 38. An adjusting screw 39 is threaded into the screw threaded portion of the bore 35 and a crank or adjusting knob 40 is provided on the end of the adjusting screw projecting out of the slide block. The end of the adjusting screw disposed inwardly of the bore 35 contacts the adjacent end of the point carrier 36, so that the point can be moved toward and away from the grinding wheel 38 by rotating the adjusting screw 39.

By reason of the magnetized bottom block 11 of the base, the grinding wheel dresser can be set on a grinding machine frame or bed adjacent a grinding wheel and will adhere to the frame or bed with sufficient force to maintain the dressing point in proper position for dressing the wheel, no brackets or clamps being required to secure the dresser to the machine frame or bed. The dresser can thus be moved from one grinding machine to another and quickly placed in operative position on a machine and can be conveniently stored when not in use. It can also be set at desired angles relative to the rotational axes of the grinding wheels to trim beveled surfaces at desired angles on the wheels.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A grinding wheel dresser comprising a base of rectangular shape including a magnetized bottom block, a top block superimposed on said bottom block and having an undercut groove extending longitudinally thereof and opening to the side of said top block remote from said bottom block, and a separator plate of non-magnetic material interposed between said top and bottom blocks, end plates secured to said base one at each end thereof and having apertures opening into said groove at the corresponding ends of the latter, a slide block mounted on said top block for sliding movement longitudinally of the latter and having a key slidably received in said groove and provided with a screw threaded aperture extending transversely therethrough, a screw shaft journaled at its ends in the apertures in said end plates and threaded through the aperture in said

key, means connected to said screw shaft for imparting rotational movements in either direction thereto to slide said slide block longitudinally of said base, said slide block having a bore extending transversely therethrough with its center line substantially at right angles to the axis of said screw shaft and inclined relative to the surface of said bottom block remote from said top block, said bore being threaded from one end to a location intermediate the length thereof, a dressing point carrier slidably mounted in said bore and projecting from the other end thereof, and an adjusting screw threaded into the screw threaded portion of said bore and projecting from said one end thereof with its end disposed inwardly of said bore in contact with the adjacent end of said point carrier.

2. A grinding wheel dresser comprising a base of rectangular shape including a magnetized bottom block, a top block superimposed on said bottom block and having a groove extending longitudinally thereof opening to the side of said top block remote from said bottom block and provided with at least one undercut side, and a separator plate of non-magnetic material interposed between said top and bottom blocks, end plates secured to said base one at each end thereof and having apertures opening into said groove at the corresponding ends of the latter, a slide block mounted on said top block for sliding movement longitudinally of the latter and having a key slidably received in said groove and provided with a beveled face adjacent the undercut side of said groove and a screw threaded aperture extending transversely therethrough, a wear plate disposed in said groove between the undercut side of the latter and the beveled face of said key, set screws extending through tapped holes in said top block and bearing at their inner ends against said wear plate to adjustably vary the pressure between said wear plate and the beveled face of said key, a screw shaft journaled at its ends in the apertures in said end plates and threaded through the aperture in said key, means connected to said screw shaft for imparting rotational movements in either direction thereto to slide said slide block longitudinally of said base, said slide block having a bore extending transversely therethrough with its center line substantially at right angles to the axis of rotation of said screw shaft and inclined relative to the surface of said bottom block remote from said top block, said bore being threaded from its end most distant from said bottom block to a location intermediate the length thereof, a dressing point carrier slidably mounted in said bore and projecting from the end of the latter nearest said bottom block, and an adjusting screw threaded into the screw threaded portion of said bore and projecting therefrom with its end disposed inwardly of said bore in contact with the adjacent end of said point carrier.

3. In a grinding wheel dresser comprising a magnetized base of rectangular shape having a flat bottom surface adapted to rest on a horizontal supporting surface adjacent a grinding wheel and having a groove extending longitudinally thereof parallel to said bottom surface and opening to its top surface, at least one side of said groove being undercut, a slide block slidably supported on said top surface and having a key slidably received in said groove and provided with a beveled face adjacent the undercut side of the groove, said key having a screw threaded aperture extending transversely therethrough, a

screw shaft extending longitudinally of said groove and threaded through the aperture in said key, means at the ends of said base journaling said screw shaft on said base, means connected to said screw shaft for imparting rotational movements thereto to move said slide block longitudinally of said base, said slide block having a bore extending transversely therethrough with its longitudinal center line substantially at right angles to the rotational axis of said screw shaft and inclined relative to the bottom surface of said base, a dressing point carrier slidably mounted in said bore and projecting from one end of the latter, and an adjusting screw threaded into said bore and projecting from the 15 other end of the latter with its end disposed in-

wardly of said bore in contact with the adjacent end of said dressing point carrier, said base comprising a body of sufficient mass to maintain the grinding wheel dresser solidly on a supporting surface.

CECIL D. CHANDLER.
